UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

TRACK FOR DOOR-HANGERS.

994,448.

Specification of Letters Patent. Patented June 6, 1911.

Application filed November 5, 1909. Serial No. 526,433

To all whom it may concern:

Be it known that I, HENRY L. FERRIS, a citizen of the United States, residing at Harvard, in the county of McHenry and State of Illinois, have invented a new and useful Improvement in Tracks for Door-Hangers, of which the following is a specification.

My invention relates to certain new and useful improvements in track for door-hangers, and is fully described and explained in the specification and shown in the accompanying drawings, in which—

Figure 1 is an elevation of a length of my improved track; Fig. 2, a section in the line 2 of Fig. 1; Fig. 3, a section in the line 3 of Fig. 2; Fig. 4, a section in the line 4 of Fig. 1, and Fig. 5 a perspective view showing one of the end-brackets, and the manner in which the lengths of track are assembled.

Referring to the drawings—A, A, are sections of a hollow-cylindrical track, each of which is open at the bottom in the form of a slot, the sections being of the type which are adapted to receive within them door-hangers, projecting portions of which extend downward through the slots to engage with the door.

B, B, are the intermediate brackets with the aid of which the sections are assembled into a complete track, the brackets having hollow-cylindrical portions adapted to receive the ends of two adjacent track-sections in the manner illustrated.

C, C¹, are the end-brackets of my track, each of the brackets having a cylindrical plug c adapted to enter the end of the adjacent section A, and center and support the same, and provided with a flange c¹, against which the ends of the adjacent sections abut.

Each of the sections A is provided at one end with a projecting tongue a, and at the other end with a corresponding notch a¹, the tongues and notches of these sections being adapted to interlock to prevent relative rotation of the sections, so as to hold the slots in the bottoms thereof in line for the continuous passage of the door-hangers.

The flange c¹ of the bracket C¹ has a projecting lug c² which enters the corresponding notch of the adjacent section A, and the flange c¹ of the bracket C is provided with a corresponding notch to receive the tongue a of the adjacent track-section.

By this construction, all the sections are held in mutual alinement by their engagement with each other and, by their engagement with the end-brackets, they are locked against bodily rotation as a unit. In this manner, a firm and substantial track construction is afforded which can readily be assembled and which can be made entirely devoid of projecting brackets. This is of particular importance, when the short-section plan of assembling is used, because one of the principal advantages of such arrangement is the fact that the track-sections can be packed and shipped without attached brackets, and where that system is used with the type of track where the hanger runs inside the track, some special means of holding the track in its original position, both absolutely with reference to the barn, and each section with respect to the other is necessary. This means is furnished in simple and convenient form in the present type of construction.

I realize that considerable variation is possible in the details of construction of my improved device, without departing from the spirit of my invention, and I do not intend therefore, to limit myself to the specific form herein shown and described.

What I regard as new, and desire to secure by Letters Patent, is—

1. In a sectional door-hanger track, the combination of a series of hollow-track sections slotted at the bottom for the passage of a door-hanger, means on the joining ends of said sections for holding the same in fixed relation to each other, intermediate brackets loosely embracing said sections, and end brackets provided with connecting means for the end sections and holding the track as a whole against rotation.

2. In a sectional door-hanger track, the combination of a series of hollow-track sections slotted at the bottom for the passage of a door-hanger, means on the joining ends of said sections for holding the same in fixed relation to each other, intermediate brackets loosely embracing the joining ends of said sections, and end brackets provided with connecting means for the end sections and holding the track as a whole against rotation.

3. In combination, a series of hollow track sections open at the bottom for the passage of a door-hanger, each section having a

- notch on one end and a tongue on the other, which parts on the adjacent sections mutually interlock to prevent relative rotation thereof, a series of brackets which loosely support the sections, and a bracket constructed to lock the end section and thereby the entire track against rotation.
4. In combination, a series of hollow-cylindrical track-sections slotted on the bottom for the passage of a door-hanger and each having a notch at one end and a tongue at the other which parts on the adjacent sections mutually interlock to prevent relative rotation of the sections, a series of sleeve-like brackets which surround the adjacent ends of each two adjacent sections and aline the same, and an end-bracket adapted to engage the tongue or notch of the adjacent section.
5. In combination, a series of hollow-cylindrical track-sections each having a tongue at one end and a notch at the other which parts on the adjacent sections mutually engage to prevent relative rotation, a series of sleeve-like brackets which surround the adjacent ends of each two adjacent sections and aline the same, and two end brackets, one provided with a notch and the other with a tongue adapted to engage the corresponding notch and tongue at the corresponding ends of the end-sections of the track.
6. In a track arrangement, a length of hollow-cylindrical track slotted at the bottom for the passage of a door-hanger and an end-bracket adapted to engage the end of said length of track and having a projection adapted to enter said slot to lock said length of track against rotation.
7. In a door-hanger arrangement, a series of hollow cylindrical track-sections slotted at the bottom for the passage of a door-hanger therethrough and provided with mutually engaging locking devices whereby when the track-sections are placed end to end in operative relation they will be held against relative rotation independent of the supporting devices.
8. In a door-hanger track arrangement, a series of hollow-cylindrical track-sections slotted on the bottom for the passage of a door-hanger therethrough, each section provided with a notch at one end and a tongue at the other whereby when the sections are placed end to end in operative relation, the notches and tongues will mutually interlock to render the sections relatively non-rotatable independent of the supporting means therefor.

HENRY L. FERRIS.
